UNITED STATES PATENT OFFICE

GEORGE C. PEDERSON, OF WEST NEW BRIGHTON, STATEN ISLAND, NEW YORK

DESIGN FOR A PLANT SUPPORT

Application filed April 8, 1933. Serial No. 47,732. Term of patent 3½ years.

To all whom it may concern:

Be it known that I, GEORGE C. PEDERSON, a citizen of the United States of America, and residing in West New Brighton, Staten Island, in the county of Richmond and State of New York, have invented a new, original, and ornamental Design for a Plant Support, of which the following is a specification, reference being had to the accompanying drawing, which forms a part hereof.

Figure 1 is a perspective view of a plant support showing my new design.

Figure 2 is a fragmentary perspective view of the upper part of Figure 1, but on an enlarged scale, for purposes of showing more clearly the details.

I claim:

The ornamental design for a plant support as shown and described.

This specification signed this 5th day of April, 1933.

GEORGE C. PEDERSON.
